UNITED STATES PATENT OFFICE.

LEOPOLD N. SPERLING AND CHARLES J. HARRIS, OF YOUNGSTOWN, OHIO; SAID HARRIS ASSIGNOR TO SAID SPERLING.

COLLAPSIBLE SCREEN FOR BABY-CARRIAGES.*

1,339,527.

Specification of Letters Patent. Patented May 11, 1920.

Application filed November 3, 1919. Serial No. 335,481.

To all whom it may concern:

Be it known that we, LEOPOLD N. SPERLING and CHARLES J. HARRIS, citizens of the United States of America, residing at 5 Youngstown, in the county of Mahoning and State of Ohio, have invented certain new and useful Improvements in Collapsible Screens for Baby-Carriages, of which the following is a specification.

10 This invention relates to a collapsible screen for baby carriages, of which the following is a clear, full and exact description.

The principal object of our invention is to provide a screen adapted to be fitted to 15 ordinary baby carriages.

Another object of our invention is to provide a collapsible screen, thus doing away with frame work. By using our improved screen, the screen may be folded, rolled up 20 and placed in any convenient storage, or carried in the baby carriage, when so desired.

A still further object of the invention is to provide a ruffle attached to the perimeter 25 of our improved screen. Within the above mentioned ruffle there is concealed a coiled spring, which is used to shape the screen so as to fit snugly over baby carriage bodies, varying in size and form.

30 The invention will be more particularly described in connection with the specific description hereinafter to be given.

Reference is to be had to the accompanying drawings forming a part of this specification, in which similar characters of reference indicate corresponding parts in all the views.

Figure 1 is a perspective view of the improved screen attached to the body and top 40 of a baby carriage; Fig. 2 is a top plan view of the device with the side wings extended; Fig. 3 is a perspective view of the device when folded and rolled.

By referring to Fig. 1, it will be seen 45 that we have provided a carriage body 1, attached to this carriage body 1 is an ordinary top 2, the screen 3 fitting securely around the front and side portions of the body 1 and the front edge of the top 2.

50 By referring to Fig. 2, it will be seen that we have provided a central portion 4; attached to this central portion 4 are wings 5 and 6. These wings are attached to the central portion 4 by means of a fabric hinge 7.

It is understood that other material than fabric may be used in making these hinges, but the material so used is to be pliable and a material which may be easily sewed. The ruffled portion 11 is attached to the perimeter of the screen 3 by means of sewing, or in any other suitable way. In placing the screen 3 upon the baby carriage we have provided a coil spring 8, with a suitable hook 9, which is used to draw the spring 65 sufficiently to fit the body 1 and the top 2 of the carriage.

By referring to Fig. 2, it will be seen we have provided a ring 10 at the lower point of the wing 6, which is used to attach this 70 portion of the screen to the body portion of the carriage.

In order to have a collapsible screen and at the same time one that will hold its shape, we have used a metallic screen. It is understood, however, that any other form of screening which has like properties, may be substituted.

Having thus described our invention, we claim as new and desire to secure by Letters Patent:—

1. In a device of the class described, the combination of baby carriage body, provided with a top, a screen comprising a central portion having parallel sides and ends, 85 hinged wings attached thereto along the sides, the hinges made of fabric, a ruffle attached to the perimeter of said central portion and wings, a coil spring held within the ruffled portion and means for attaching the ends of said spring, substantially as described for the purposes set forth.

2. In a device of the class described, a baby carriage screen comprising a central portion having parallel ends and sides, side 95 wings attached thereto by means of fabric hinges, a ruffle attached to the perimeter of the screen, a coil spring carried within the ruffle, substantially as described for the purposes set forth.

100 In testimony whereof we affix our signatures.

LEOPOLD N. SPERLING.
CHAS. J. HARRIS.
